UNITED STATES PATENT OFFICE.

GUSTAV DIECKMANN, OF SAN FRANCISCO, CALIFORNIA.

FOLDABLE DRYING-CABINET.

1,135,267.

Specification of Letters Patent. Patented Apr. 13, 1915.

Application filed June 2, 1914. Serial No. 842,354.

To all whom it may concern:

Be it known that I, GUSTAV DIECKMANN, a citizen of the United States, residing in the city and county of San Francisco and State of California, have invented new and useful Improvements in Foldable Drying-Cabinets, of which the following is a specification.

This invention relates to a foldable drying cabinet.

It is one of the objects of the present invention to provide a simple, substantial, cheaply manufactured, foldable drying cabinet which is particularly adapted for use in kitchens and small laundries where space must necessarily be considered.

Another object of the invention is to provide a novel support for the heater within the cabinet, and means for introducing air thereto; and also to provide baffle plates by which the heated air may be thoroughly circulated within the cabinet and the moist air discharged therefrom. Further objects will hereinafter appear.

The invention consists of the parts and the construction and combination of parts as hereinafter more fully described and claimed, having reference to the accompanying drawings, in which—

Figure 1 is a central vertical section, in side elevation, of the cabinet, showing it in the extended position. Fig. 2 is a plan section on the line $\alpha-\alpha$, Fig. 1. Fig. 3 is a section similar to Fig. 1, showing the cabinet in the folded position. Fig. 4 is a plan view of the cabinet, showing it in the folded position. Fig. 5 is a detail of the top supporting latch. Fig. 6 is a detail vertical section of one of the hollow pivot members.

Referring to the drawings, A indicates the folding cabinet in general and B a wall or support to which the cabinet is suitably secured. The cabinet in general consists of a stationary rear section 2, to which side extensions 3 and 4 and a top section 5 are rigidly secured. The side extensions 3 and 4, together with the top section 5, form a pocket which is adapted to receive the heater and other parts of the cabinet when this is collapsed or folded, as hereinafter described. The side panels of the cabinet are in this instance hingedly supported, as at 3^a and 4^a, on the stationary side extensions 3 and 4. Each side panel is, however,

centrally divided, as at 6, and the two sections thus formed are connected together by hinges 7. This permits the side panels to be folded inwardly about the hinges 3^a, 4^a and 7 to assume the position indicated in Figs. 3 and 4. The front panel of the cabinet, indicated at 8, is supported by the side panels through means of hinges 9, so that it will move in and out as the panels are folded or extended. The front panel is otherwise provided with a pair of doors 9 and 10 mounted upon hinges 11, through which admission may be gained to the cabinet. The top of the cabinet is supported and secured quite similar to the side panels; that is, the top is centrally divided, as at 12, and the sections thus formed are connected together by hinges 13. The inner edge of the top is supported by hinges 14 to the top section 5, and the outer section of the top is adapted to be carried by latches 15 mounted on the inner sides of the side panels. The other section of the top is also supported by latches, as indicated at 16. Each section of the top is thus independently supported with relation to the side panels.

When closing or folding the cabinet, it is accomplished by opening the front doors 9 and 10. The latches 15 are then depressed and the front pivoted section of the top will then be permitted to drop down in the direction of arrow a . It is then swung inwardly into the dotted line position indicated at 17 for the purpose of automatically releasing the latches 16. The inward movement of the front section of the top to the dotted line position indicated at 17 causes the outer edges of same to engage with inclined faces 18 of the latches 16 and will consequently force the same inwardly a sufficient distance in the direction of arrows b to release the inner section of the top. The two sections are then folded back and allowed to take the position indicated in Fig. 3. The bottom of the cabinet is in the instance shown as consisting of a metal pan 19, which is pivotally mounted, as at 20 and 20^a, in the lower ends of the stationary side sections 3 and 4. Suitably secured at about the center of said pan is a suitable form of burner 21, and entirely inclosing same is a hood 22 which is connected through a flattened flue 23 with a chamber 24. Connecting said chamber 24 with the pivot points 20 and 20^a, which are hollow, are discharge flues 25 and 25^a. The

burner, indicated at 21, is preferably supplied by gas through a flexible hose connection 26 which may be attached through the usual form of connection, indicated at 5 27, when the cabinet is extended and the pan lowered into the position indicated in Fig. 1.

Running parallel with the sides of the pan, and projecting a suitable distance above the bottom of same, is a pair of baffle 10 plates 28 and 29, one being mounted on each side, and connecting the outer ends of the channels thus formed with the hood 22 is a pair of inlet flues 30 and 31. The pivot points 20 and 20^a are hollow and will 15 thus form communication with outside flues C and the channels formed between the baffle plates 28 and 29 and the sides of the pan. The air for drying purposes is admitted through a series of perforations 32 20 formed in the bottom of the pan directly under the flue 23. The baffle plates also prevent the direct escape of the fresh air admitted through the perforations 32 before it has become heated and performed 25 its required function.

The operation will be as follows: If the cabinet is standing in the folded position shown in Figs. 3 and 4 and it is desired to extend it into operating position, it is accomplished by first releasing a pair of side 30 hooks 33, then pulling the front panel 8 in an outward direction which is limited when the side panels assume the straight position. The bottom or pan 19 is then lowered down 35 and the inner section of the top panel is raised until it is engaged by the latches 16. The outer section is next raised until it is engaged and supported by the latches 15. A wire section or false bottom 34, hingedly 40 secured to the rear section 2 of the cabinet, is then dropped down and is supported by legs 35. The flexible gas hose connection 26 is then connected and the burner started. Secured to the front and side panels at their 45 upper and lower ends are angle-iron strips 40; the lower strips forming a support for the pan, while the upper strips form a stop or butt which not only limits the upward movement of the cover sections but also aids 50 to form a tight joint between the cover and the front and side panels, which prevents leakage or escape of heat at the upper end of the cabinet. The lower supporting strips also have the same function, that is, they 55 prevent the admission of cold air around the edges of the pan.

The latches 15 and 16 are shown as mounted in tapered blocks 15^a and 16^a. These are provided both as guides to bring the cover 60 sections into engagement with their respective supporting latches and as spacers or liners which hold the cover sections in juxtaposition between the side panels.

Air to supply the burner is admitted 65 through the inlet flues 30 and 31 from the

side channels formed between the sides of the pan and the baffle plates 28 and 29. The products of combustion from the burner will then flow out through the flue 23, chamber 24 and discharge flues 25 and 25^a and 70 will finally escape through the hollow pivot connection 20 and 20^a, which are connected with the outside flues C and chimney, or the like, not here shown, or may escape directly into the room.

The hood 22, together with the flues 23 and 25 and the hood covering chamber 24, will thus become thoroughly heated and fresh air from the outside will be admitted through the perforations 32 formed in the 75 bottom of the pan. This air passing around the flue 23 and hoods 22 and 24 will become thoroughly heated and will consequently rise up through the center of the cabinet to finally become deflected by the 80 top. The air gradually cooling by coming in contact with moist clothing or similar articles suspended by rods indicated at 36, will thus gradually cool and will settle down along the interior surface of the side 85 panels and will finally enter the side channels formed between the baffle plates 28 and 29 and the sides of the pan. The air thus partly cooled and moistened by contact with the clothing is partly consumed 90 by entering through the inlet flues 30 and 31. While the greater portion will escape through the hollow pivot connections 20 and 20^a fresh dry air is in the meantime continuously entering through the perforations 95 32. A continuous supply of fresh, dry, heated air is thus supplied while the cooler and moistened air is partly consumed by the burner or permitted to escape through the connections 20 and 20^a. The clothing or 100 other articles suspended within the cabinet or supported upon the screen 34 is thus quickly and thoroughly dried.

Referring to Fig. 6, it will be seen that the ends of the flues 25 and 25^a are preferably extended into the main outlet flues C and turned up as indicated at 41. This construction greatly increases the suction through the hollow pivot connections, as the products of combustion are directed 110 right up into the main outlet flues. A more or less forced draft and siphon action are thus produced with consequent draft increase through the hollow pivot connections where most of the moist cooled air escapes. 115

The cabinet, when not in use, may be quickly folded by first opening the front doors 9 and 10 and releasing the outer section of the top by depressing the latches 15. The inner section of the top is then released 120 by swinging the outer section toward the dotted line position indicated at 17, which automatically depresses the latches 16 to release the inner section of the top. The pan is next raised into the position indicated in 125 130

Fig. 3. The released top sections are then folded in toward the rear section of the cabinet and the front panel moved inwardly while the side panels are folded together. 5 The several parts of the cabinet are thus compactly folded and may be secured in this position by the hooks 33 or other means. The cabinet consumes very little space, when folded, and may be folded or extended with 10 very little effort, and is of such simple construction that it may be handled and successfully operated by any one.

Having thus described my invention, what I claim and desire to secure by Letters Patent is—

1. A folding cabinet comprising a stationary rear section having top and side extensions rigidly secured thereto, foldable side panels hingedly supported on said side extensions, a front panel hingedly supported by the side panels, a foldable top hingedly secured to the top extension, means carried by the side panels to support the foldable top, hollow pivot members mounted in the 25 lower ends of the side extensions, a pan carried by said pivot members, said pan being adapted to fold up between the side extensions or fold down to form a bottom for the cabinet, a heater mounted on said pan, a 30 hood inclosing the heater, and discharge flues connecting the hood with the hollow pivot members.

2. A folding cabinet comprising a stationary rear section having top and side extensions rigidly secured thereto, foldable side panels hingedly supported on said side extensions, a front panel hingedly supported by the side panels, a foldable top hingedly secured to the top extension, means carried by the side panels to support the foldable top, hollow pivot members mounted in the 40 lower ends of the side extensions, a pan carried by said pivot members, said pan being adapted to fold up between the side extensions or fold down to form a bottom for the cabinet, a heater mounted on said pan, a 45 hood inclosing the heater, perforations formed in the bottom of the pan for the admission of fresh dry air, and means for conveying moist air from within the cabinet to the heater.

3. A drying cabinet of the character described having a pair of hollow pivot members mounted therein, a pan carried by said 55 pivot members, said pan forming a foldable bottom for the cabinet, a gas burner secured on the pan, a hood inclosing said burner, discharge flues connecting said hood with the hollow pivot connections, perforations 60 formed in the pan under the discharge flue through which fresh air is admitted to the cabinet and heated, inlet flues connected with the hood, and baffle plates connected with said inlet flues to gather and direct 65 moist air formed within the cabinet to the

burner and also to direct a portion of the moist air out through the hollow pivot members.

4. A folding cabinet comprising a stationary rear section having top and side extensions rigidly secured thereto, foldable side panels hingedly supported on said side extensions, a front panel hingedly supported by the side panels, a foldable top hingedly secured to the top extension, means carried by the side panels to support the foldable top, hollow pivot members mounted in the 70 lower ends of the side extensions, a pan carried by said pivot members, said pan being adapted to fold up between the side extensions or fold down to form a bottom for the cabinet, a heater mounted on said pan, a 75 hood inclosing said heater, and discharge flues connected with said hood at one end and extending into the hollow pivot connec- 80 tions at their other ends.

5. A folding cabinet comprising a stationary rear section having top and side extensions rigidly secured thereto, foldable side panels hingedly supported on said side 85 extensions, a front panel hingedly supported by the side panels, a foldable top hingedly secured to the top extension, means carried by the side panels to support the foldable top, hollow pivot members mounted in the 90 lower ends of the side extensions, a pan carried by said pivot members, said pan being adapted to fold up between the side extensions or fold down to form a bottom for the cabinet, a heater mounted on said pan, a 95 hood inclosing said heater, discharge flues connected with said hood at one end and extending into the hollow pivot connections at their other ends, means for admitting cool 100 air to the cabinet and heating same, and 105 means for conveying air from within the cabinet to the heater.

6. A drying cabinet of the character described, having a pan foldably mounted therein to form a bottom for the cabinet, a 110 gas burner secured on the pan, a hood inclosing said burner, main discharge flues on the sides of the cabinet communicating at their lower ends with the interior of the cabinet, interior discharge pipes secured by 115 the pan connected at their inner ends with the burner hood and having their outer ends extending into the lower ends of the main discharge flues, and perforations in the bottom of the pan under the interior discharge 120 flues through which fresh air is admitted to the cabinet and heated.

7. A drying cabinet of the character described, having a pan foldably mounted therein to form a bottom for the cabinet, a 125 gas burner secured on the pan, a hood inclosing said burner, main discharge flues on the sides of the cabinet communicating at their lower ends with the interior of the cabinet, interior discharge pipes secured by 130

the pan connected at their inner ends with the burner hood and having their outer ends extending into the lower ends of the main discharge flues, and perforations in the bottom of the pan under the interior discharge flues through which fresh air is admitted to the cabinet and heated, and inlet flues connected with the hood, and baffle plates connected with said inlet flues to gather and direct moist air formed within the cabinet

to the burner and also to direct a portion of the moist air out through the main discharge flues.

In testimony whereof I have hereunto set my hand in the presence of two subscribing 15 witnesses.

GUSTAV DIECKMANN.
